REPLACEABLE LEADER PIN BUSHING

Kasimir Janiszewski, Milwaukee, Wis.

Application September 12, 1950, Serial No. 184,366

9 Claims. (Cl. 308—4)

This invention relates to improvements in replaceable leader pin bushings.

The invention consists in substituting for conventional leader pin bushings an easily replaceable bushing which is seated in such a manner to be accurately aligned with the pin and to maintain such alignment during die set operation.

In conventional die sets comprising a punch holder mounted for reciprocable movement toward and from a die shoe, it is of the utmost importance that the reciprocable movement of the die parts be accurately guided so that the punch holder will not deviate laterally; otherwise the work being formed between the die parts will be subject to alignment inaccuracies with resultant lowering of the quality of work produced. For the purpose of guiding the reciprocating movement of the punch holder, the die shoe is conventionally provided with several upstanding leader pins which are telescopically receivable within punch holder bushings seated in suitable through apertures in the punch holder.

Heretofore it has been the practice to press fit the punch holder bushings in their seats. The internal stresses in the bushing by this practice tend to distort the accurately machined form of the bushing, and it has been a routine necessity to relap the bushing bore to correct the axial alignment of the bushings and leader pins. In some extreme cases the bushing bore axis was laterally displaced to such an extent as to make it advisable to rebore the punch holder apertures and insert oversized bushings.

It is the principal object of this invention to provide a replaceable leader pin bushing which need not be seated in the punch holder aperture with a press fit, but which may be merely hand or tap fitted into its seat. Consequently no distortion of the leader pin bushing wall occurs and it is possible to accurately machine and lap the bushing bore prior to seating with no further lapping being necessary after the bushing is in place. Furthermore the removal of the bushing from its hand pressed position becomes a simple matter and the bushing may be easily replaced when worn.

It is a further object of the invention to provide a tap fitted punch holder bushing with means external of the inner walls of the punch holder aperture, and independent of bushing wall resiliency, for securely positioning the bushing in axial alignment with the leader pin.

In this connection it is an object of the invention to provide a bushing which comprises a bearing sleeve having an external collar providing a shoulder intermediate the sleeve end margins which is abuttable in stabilizing fixed position against the under surface of the punch holder and which is provided with means for fastening said collar and punch holder into a unitary structure.

Another object of the invention is to laterally offset the punch holder connected portion of the collar from the sleeve to utilize collar resiliency whereby the exposed portion of the bushing is yieldable laterally for shock absorbing and self realignment purposes.

Another object of the invention is to fabricate the sleeve and collar from oppositely seamed rolled sheets to strengthen the complete unitary bushing.

Other objects will be more apparent to one skilled in the art upon an examination of the following disclosure.

In the drawings:

2

Fig. 1 is a side elevational view of an assembled die set embodying the present invention with portions adjacent one of the leader pins being shown in cross section.

Fig. 2 is a cross sectional view taken along the line 2—2 of Fig. 1.

Fig. 3 is a fragmentary cross sectional view of the punch holder showing the details of a modification of the bushing.

Fig. 4 is a fragmentary cross section of the punch holder showing a further modification of the bushing.

Fig. 5 is a bottom view of the structure shown in Fig. 4.

Fig. 6 is a cross sectional view of a modification of the bushing showing the collar in the shape of a frustum of a right cone with an annular space between the bushing sleeve and collar.

Fig. 7 is a bottom view of the bushing shown in Fig. 6.

Fig. 8 is a fragmentary view of a modification of the mounting of the bushing shown in Fig. 6.

The die set comprises spaced platens conventionally referred to as a die shoe 10 and a punch holder 11. The punch holder is mounted for reciprocal movement toward and from the die shoe 10. The movement of the punch holder is guided in its reciprocation and against deviation by a leader pin 12 which is securely mounted in upstanding position in a mounting insert 13. The leader pin and mount as illustrated have complementary mating tapers which comprise the claimed subject matter of a companion application for patent entitled "Tapered Leader Pin and Die Shoe Bushing Assembly" executed of even date herewith.

The punch holder 11 is provided with several through apertures 14 which provide seats for the bushing sleeves 16. The bushing sleeves 16 are axially aligned with the leader pins 12 and provide a bearing surface or bore 17 in which the pin is telescopically receivable to guide the punch holder.

Sleeve 16 is intended to be tap or hand pressed into seated position in the bore 14 and for this purpose is made of but slightly larger external diameter than the internal diameter of bore 14. The difference in diameters is desirably in the range of five ten thousandths of an inch. Accordingly, some slight pressure is required to seat the sleeve into the bore. This difference in diameter is very much less than that required heretofore for a press fit, the difference for a press fit is conventionally in the range of twenty-five ten thousandths of an inch. The requirement of a hand or tap fit facilitates the assembly of the bushing and punch holder and axial alignment of the sleeve with the pin is assured.

The inner bearing surface 17 of the sleeve 16 is accurately machined and lapped to perfect sliding fit and alignment with the leader pin 12 prior to seating the sleeve within the punch holder apertures. The tap or hand fit of the sleeve does not distort the bearing walls 17 of the sleeve, as is sometimes the result of a press fit; consequently such surfaces do not require relapping after seating.

In order to securely mount the sleeve in the punch holder, the bushing sleeve is made of such a length that when properly seated a portion of the sleeve will extend below the squared under surface 20 of the punch holder 11. The rigid positioning of the sleeve 16 in its punch holder seat 14 is accomplished by means of a collar 21 (Figs. 1 and 2) which is fixed by welding or the like to the outer periphery of the sleeve 16. The collar provides an annular edge or shoulder 22 which is squared with respect to the axis of the leader pin to abut the under surface 20 of the punch holder and insure the axial alignment of the sleeve with the leader pin. The collar also provides a means for fastening the bushing to the punch holder, to augment the tap or hand fit therebetween, as will be hereinafter more fully described.

In the embodiments of the invention shown in Figs. 1 to 5 the respectively illustrated sleeves and collars are cylindrical. The collars are normally made integral with the sleeves, at only one annular edge 23 of the collar. In the modification shown in Figs. 6 to 8, however, the collar 24 comprises a frustum of a right cone, and has a tapered inner periphery 25 which is welded at 26 or otherwise made integral at its upper base with the projecting end margin of sleeve 16. Shoulder 27 of collar 24, which comprises the lower base of the cone frustum, is consequently laterally offset from the outer periphery of the sleeve 16, thus forming an annular tapered space, indicated as 28, between the sleeve and collar. The collar is preferably made of resilient metal. Accordingly, the portion of the sleeve below the confines of the punch holder 11 is provided with a resiliently yielding lateral support which will yield slightly upon lateral shock and return the sleeve to proper axial alignment thereafter.

The bushing may be relatively rigidly secured in its axially aligned seated position by holding the collar tight against the under surface of the punch holder in a variety of fashions. As best shown in Figs. 6 and 7 the collar may be tack welded at 31 to the punch holder. As in Fig. 8 the collar may alternatively be provided with peripherally spaced mounting ears 32 which register with punch holder tabs 34 to receive bolts 33 which draw the shoulder 27 of the collar firmly against the squared under surface of the punch holder.

In the embodiment shown in Figs. 1 to 5 the collar is provided with a series of arcuately spaced transverse apertures or sockets 35, into which fingered portions of arms 36 (Fig. 4) or 39 (Fig. 1) extend. The opposite ends of the arms may be either bolted, as shown at 37 of Fig. 4, or tack welded, as shown at 38 in Figs. 1 and 3, to the punch holder. Any desired number of collar sockets and arms may be provided. As shown in Fig. 2 two diametrically oppositely disposed arms and sockets are provided. In Fig. 5 three arms and sockets are shown mutually spaced at 120° angles.

The exact shape of the arms 36 and 39 is broadly immaterial; a double fingered arm 46 is shown in Fig. 3 and single finger arms 36 and 39 are shown in Figs. 1 and 4. If desired the material of which the arms are made may be of relatively soft metal to permit a screw driver blade to be inserted between the arm and collar to pry the fingers from the collar sockets without breaking the tack welds. The bushing may then be removed and a new bushing inserted and the fingers inserted in the respective sockets of the new bushings to bring the collar shoulder up tight against the punch holder.

The bushings may be removed from their seats for replacement or the like simply by loosening the bolts and tapping the sleeves downwardly from its seat. When the arms are tack welded, the welds may be broken by a sharp blow on the upper end margin of the sleeves to force the sleeves from their seats.

If desired the bearing surface may be lubricated by providing the collar with an oil reservoir formed between a channeled portion of the collar and the sleeve (Fig. 3). The collar is further provided with a filler tube 43 accessible exteriorly of the collar and one or more oil ducts 44 leading to an oil groove 45 in the bearing surface of the bushing sleeve.

In order to increase the strength of the sleeve and collar to prevent distortion and buckling, the sleeve and collar may be separately rolled and formed from sheet stock and provided with welded seams which are disposed diametrically opposite each other in the assembled collar and sleeve. This construction is best shown in Fig. 7. In this manner internal stresses tending to deform the bearing surfaces balance each other and misalignment of the leader pin and sleeve axis is prevented.

From the foregoing description, it is evident that by providing the bushing sleeves with the shouldered collars

only a tap fit need be employed to seat and align the sleeve axially with the leader pin thus eliminating press fit distortion of the bushing. As a result, bearing surfaces can be lapped prior to assembly with the assurance that they will remain accurate when seated. Furthermore the specific arrangement in Fig. 6, wherein the shouldered portion of the collar is offset laterally from the outer sleeve periphery, accentuates the resilient spring characteristic of the collar and enables the bushing to absorb lateral shock without misalignment. The bushings are easily removed with hand tools without damage to the punch holder seats and a replacement bushing may be reinserted in the same seat without it being necessary to drill new holes to receive oversized bushings.

15. I claim:

1. The combination with a die set platen having an aperture and a bushing in said aperture, said bushing comprising a sleeve having an extension beyond said platen, of a collar comprising a cylindrical wall co-axial with the sleeve extension and connected thereto, one end margin of the collar comprising a shoulder for abutment against the platen, said collar being provided with exposed sockets, and arms engaged in said sockets, said arms having means radially spaced from said collar for mounting said arms to the platen whereby the collar and sleeve extension are free for limited lateral yielding within said space.
2. The combination with a die set platen having a face, an aperture, and a bushing in the aperture, said bushing comprising a sleeve having an extension beyond said platen face, of a collar comprising a wall co-axial with and enclosing the sleeve extension, one end of the collar being connected to the end of the sleeve extension and the other end of the collar constituting a shoulder in abutment against the platen face, and means connected with the collar and rigidly united with the face of the platen for connecting said collar to the platen.
3. The device of claim 2 in which the collar is provided with an annular chamber constituting an oil reservoir, said sleeve having a duct leading therefrom to the interior of the sleeve.
4. The device of claim 2 in which the connecting means comprises arms, the collar having laterally open sockets in which the arms are engaged, and the arms having means radially spaced from the collar for rigidly connecting the arms to the platen.
5. The device of claim 2 in which the wall of the collar is, at its outer end, the inner end margin of the collar being offset radially from the sleeve, the collar portion intermediate said ends providing resilient support for said sleeve.
6. The device of claim 2 in which the sleeve and collar comprise tubes having axial seams in diametrically opposite positions.
7. The device of claim 2 in which the connecting means includes a weld to said face.
8. The device of claim 2 in which the connecting means includes a plurality of screws threaded into the platen through said face.
9. The device of claim 2 in which the sleeve comprises a leader pin bushing having a relatively loose fit in the said platen aperture and dependent for position on said collar and said connecting means, the rigid union of the latter to the platen face being offset radially from the bushing and substantially symmetrical about the bushing sleeve, whereby to position the sleeve accurately and with a degree of resilience between the sleeve and the rigid union to the platen.
